PAPER HANGING MACHINE

Wallace H. Johnson, Akron, Ohio

Application February 12, 1938, Serial No. 190,282

21 Claims. (Cl. 216—6)

This invention relates to paper hanging machines, such as are used for hanging wall-paper, billboard posters, and the like.

One object of the invention is to provide an improved paper hanging machine of the character described which is of simple, compact, light weight, inexpensive construction, and which can be loaded for use with a minimum of effort expended in threading the end of the paper roll past the paper guiding means.

Another object is to provide a machine of the character described which will apply an even coat of adhesive material to the reverse side of a roll of paper as the latter is being drawn from the machine for application to a surface to be prepared, and to apply such adhesive material to the extreme edges of the paper.

Another object is to provide a machine of the character described by means of which the edge of the paper may be applied substantially close to corners.

Another object is to provide a machine of the character described for applying paper to corner surfaces.

Another object is to provide a machine of the character described which may be adapted to accommodate paper of varying widths.

Another object is to provide a machine of the character described which may be used equally as well for applying paper to overhead surfaces, as for vertical surfaces.

Another object is to provide a machine of the character described having an improved valve means for regulating the flow of adhesive material to the paper without appreciable leakage.

Another object is to provide a machine of the character described having improved means for smoothing the paper as it is applied to a surface being papered.

Another object is to provide a machine of the character described having improved paper trimming as means thereon.

Other objects of the invention will be apparent from the following brief description and the accompanying drawings.

Of the accompanying drawings:

Figure 1 is an end view of a paper hanging machine embodying the invention.

Figure 2 is a front elevation thereof.

Figure 3 is a cross-section taken substantially on line 3—3 of Figure 2.

Figure 4 is a fragmentary cross-section, partly broken away, taken on line 4—4 of Figure 3.

Figure 5 is a fragmentary cross-section taken on line 5—5 of Figure 4.

Figure 6 is a fragmentary cross-section taken on line 6—6 of Figure 3.

Figure 7 is a rear elevation of Figure 1.

Figure 8 is a view similar to Figure 4 illustrating the use of the adapter for paper of a narrower width.

Figure 9 is a fragmentary cross-section taken on line 9—9 of Figure 8.

Figure 10 is a rear elevation, partly broken away, of a machine having a modified form of brush thereon.

Figure 11 is an enlarged end view, as viewed from the left of Figure 10 in the chain-dotted position thereof.

Referring to Figures 1 to 7, inclusive, of the drawings, the numeral 10 indicates a paper hanging machine, preferably cylindrical in shape, having a receptacle 11 defined by an outer wall 12, inner wall 13 and end walls 14, 14, for retaining a suitable adhesive fluid 15, such as paste. 20 Adjacent the receptacle 11 there may be a cylindrical compartment 16 defined by a portion of inner wall 13 and a wall 17 extending between the walls 14, 14, the wall 17 being carried by a gate member 18 pivotally mounted at 19, 19 on 25 the walls 14, 14. The gate member 18 is adapted to be swung outwardly, as shown in chain-dotted lines in Figure 3, to receive, loosely but without end play, a roll of paper 20 of standard width, such as wall-paper. Releasable spring clips 21, 30 21 may be secured on wall 13, adapted to engage projections 22, 22 on gate member 18 to hold the latter firmly in closed position. A closure, preferably flush with an end wall 14, may be provided at 23 for filling the receptacle 11 with 35 adhesive fluid 15.

Adjacent the lower region of inner wall 13 there may be provided a relatively narrow valve slot or opening 24 extending lengthwise between the walls 14, 14. Yieldably mounted on gate member 18, for pressing engagement with the inner wall 13, there may be a pair of spaced, parallel rollers 25 and 26 adapted to hold the paper 20^a, as it comes from roll 20, stretched across the opening 24, the paper 20^a thereby providing an effective valving means for controlling the flow of the fluid 15 at the opening 24. A plate 27 having a series of relatively small openings 28 therein is provided to reinforce the wall 13 adjacent the opening 24. The wall 13 may 50 bend outwardly at 13^a to flex the paper 20^a at the lower edge of the opening 24 to thereby more effectively seal the same.

Roller 25 may be suitably journaled on arms 29, 29, pivotally mounted at opposite ends of 55

gate member 18, and for yieldingly urging roller 25 toward wall 13, there is provided a spring 30. A pin 30^a, on gate member 18, is provided for limiting the swing of arms 29.

5 The roller 26 may be journaled on blocks 31, 31 carried by rods 32, 32, slidably mounted in lugs 33, 33 and 34, 34 on gate member 18. For yieldingly urging roller 26 there may be provided springs 35, 35 between lugs 34 and adjusting nuts 36, 36, the latter being one means for regulating the amount of adhesive fluid to be applied to the paper 20^a through opening 24.

10 Gate member 18 preferably is provided with a smooth surfaced, curved outer wall 18^a over which the paper 20^a may be drawn as it is applied to a surface to be papered, a brush 37 being provided on outer wall 12, above gate member 18, for pressing and smoothing the paper against such surface.

15 20 The machine 10 may be provided with an inversely curved handle 38 having recessed portions 39 and 40 adapted to be received over the back of a chair or a board, so that machine may be hung either in a substantially upright position when not in use, or in inverted position when it is desired to insert a roll of paper in the machine while there is adhesive fluid in receptacle 11.

25 30 A supplementary valve flow control mechanism may be provided so that the operator of the machine may control to a substantial degree the amount of adhesive flowing to the paper 20^a while the machine is in use. To this end there is provided an arm 42 pivotally mounted to handle 38 and having at its free end a roller 43 adapted to be urged against roller 26 with the paper 20^a thereon. For urging the roller 43 in this manner there is provided an extension 42^a adapted to be gripped by the operator's finger or fingers with the desired degree of pressure as he operates the machine. When it is desired to hang the machine 10 by the handle in upright position as above stated the arm 42 may be swung outwardly out of the way.

35 45 For slitting the paper 20^a lengthwise as it is being drawn from the machine 10 there may be provided a knife 44 adapted to cut the paper against roller 26. The knife 44 is pivotally supported on an arm 45, the latter being pivotally and adjustably secured on a longitudinal shaft 46 supported on outer wall 12.

50 55 Slidably retained between the inner wall 17 and outer wall 18^a of gate member 18, there may be a knife supporting carriage or block 47 (see Figures 3 and 6), having pivotally mounted thereon a knife 48 for slitting the paper 20^a widthwise. Knife 48 is adapted to be swung outwardly from the full line position to the chain-dotted position, shown in Figure 6, and then swung downwardly to permit its being drawn across the width of the paper, guided by a slot 49 in wall 18^a.

60 65 At each end of the valve opening or slot 24 there is provided downwardly inclined plate 50, so arranged that the paper 20^a barely contacts plates 50 at its extreme edges, thereby insuring that the adhesive fluid 15 will reach every portion of the paper 20^a exposed to the valve opening or slot 24, without appreciable leakage past said edges of the paper.

70 75 Referring to Figures 8 and 9, 51 is an adapter plate which may be clipped or sprung over plate 50, to serve the same purpose as plate 50, whenever it is desirable or necessary to use paper of narrower width in the machine than has been

heretofore described. The plate 51 is provided with a downwardly extending portion similar to plate 50 and in addition has a flange 52 thereon for guiding the edge of the paper 20^b. The plates 51 may be supplied in various sizes to accommodate different widths of paper and they may be inserted at both ends of the opening 24.

75 80 Figures 10 and 11 show a form of pressing and smoothing brush 53 adapted to be used in addition to or in place of brush 37. Brush 53 may be 10 made in two parts 53^a, 53^b, pivotally connected by a thumb screw at 54 and slidably secured to the paper hanging machine 10^a by means of clamps at 55, 55, the arrangement being such that the brushes may be set angularly of each other for use in reaching into corners during the paper applying operation. Brush 53^b may be provided with a longitudinal slot 56 so that by loosening thumb-screw 54 and clamps 55, the brushes 53^a and 53^b may be collapsed to the position shown 15 in chain-dotted lines in Figure 10 and in full lines in Figure 11. In the latter position the brush 53 may be used for flat surfaces in place of brush 37.

20 25 In the use of the machine a roll of paper 20 may be inserted in compartment 16 when machine 10 is in inverted position if there is adhesive fluid 15 in receptacle 11. Otherwise the roll may be placed in position when the machine is substantially in the chain-dotted position 30 shown in Figure 3. In either case it is a very simple matter to place the roll of paper 20 against the inner wall 17 of gate member 18 when the latter is in open position, at the same time passing the leading end of the roll between the inner wall 13 and the adjacent parts of the gate member 18. The next step is merely to close gate member 18, thereby bringing rollers 25 and 26 to a position to press the paper 20^a over the valve opening or slot 24. Thus the paper 20^a stretched 40 across the opening 24 between rollers 25 and 26 serves effectively as a valve to regulate flow of fluid 15 at the opening 24. Drawing the leading end of the roll 20 around roller 26, over the outer surface of wall 18, and over the brush 37, after the machine is placed in the full line position shown in Figure 3, applies a coat of adhesive fluid evenly over the surface of the paper and the latter may then be applied, for example, in the case of a vertical wall surface, with a steady downward stroke. Obviously, the machine may be just as effectively used for applying paper to overhead surfaces, such as the ceiling of a room.

45 50 Modifications of the invention may be resorted to without departing from the spirit thereof or 55 the scope of the appended claims.

What is claimed is:

1. A paper hanging machine, comprising a casing for containing adhesive fluid, means connected to said casing for supporting a roll of paper in association therewith, said casing having an adhesive applying opening therein, and means for guiding said paper across said opening to apply adhesive to the paper, said guiding means including spaced yieldable elements on 60 opposite sides of said opening for yieldingly urging said paper against said opening to close the same.

2. A paper hanging machine, comprising a casing for containing adhesive fluid, means connected to said casing for supporting a roll of paper in association therewith, said casing having an adhesive applying opening therein, and means for guiding said paper across said opening to apply adhesive to the paper, said guiding 70 75

means including spaced yieldable rollers on opposite sides of said opening for urging said paper against said opening to close the same.

3. A paper hanging machine, comprising a casing for containing adhesive fluid, means connected to said casing for supporting a roll of paper in association therewith, said casing having an adhesive applying opening therein, means for guiding said paper across said opening to apply adhesive to the paper, and members extending angularly inwardly of the opening at the opposite ends thereof for contacting said paper at the edges thereof to seal the opening but permitting flow of said fluid to the edges of the paper.

15 4. A paper hanging machine, comprising a casing for containing adhesive fluid, means connected to said casing for supporting a roll of paper in association therewith, said casing having an adhesive applying opening therein, means for guiding said paper across said opening to apply adhesive to the paper, and removable and replaceable members extending angularly inwardly of said opening at the opposite ends thereof for contacting said paper at the edges thereof to seal the opening but permitting flow of said fluid to the edges of the paper.

25 5. A paper hanging machine, comprising a casing for containing adhesive fluid, means connected to said casing for supporting a roll of paper in association therewith, said casing having an adhesive applying opening therein, means for guiding said paper across said opening to apply adhesive to the paper, said guiding means including spaced yieldable elements on opposite sides of said opening for yieldingly urging said paper against said opening to close the same, and means associated with said guiding means for adjusting the pressure of said paper against said opening.

35 40 6. A paper hanging machine, comprising a casing for containing adhesive fluid, means connected to said casing for supporting a roll of paper in association therewith, said casing having an adhesive applying opening therein, means for guiding said paper across said opening to apply adhesive to the paper, said guiding means including spaced yieldable elements on opposite sides of said opening for yieldingly urging said paper against said opening to close the same, and means associated with said guiding means for adjusting the pressure of said paper against said opening.

45 55 7. A paper hanging machine, comprising a casing for containing adhesive fluid, means connected to said casing for supporting a roll of paper in association therewith, said casing having an adhesive applying opening therein, means for guiding said paper across said opening to apply adhesive to the paper, said guiding means including spaced yieldable elements on opposite sides of said opening for yieldingly urging said paper against said opening to close the same, and means for flexing said paper over the lower edge of said opening to seal the same.

60 65 8. A paper hanging machine, comprising a casing for containing adhesive fluid, means connected to said casing for supporting a roll of paper in association therewith, said casing having an adhesive applying opening therein, means for guiding said paper across said opening to apply adhesive to the paper, said guiding means including spaced yieldable elements on opposite sides of said opening for yieldingly urging said paper against said opening to close the same, and means associated with said

guiding means for adjusting the pressure of said paper against said opening, and means for flexing said paper over the lower edge of said opening to seal the same.

9. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, and means on said gate member for guiding said paper across said adhesive applying opening to apply adhesive to the paper, whereby said gate member may be swung open for loading a roll of paper in said compartment and said guiding means being thereby swung away to permit free insertion of said paper between said adhesive applying opening and said guiding means.

10. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, and means on said gate member for guiding said paper across said adhesive applying opening to apply adhesive to the paper, whereby said gate member may be swung open for loading a roll of paper in said compartment and said guiding means being thereby swung away to permit free insertion of said paper between said adhesive applying opening and said guiding means, said guiding means including spaced yieldable elements on opposite sides of said adhesive applying opening for urging said paper against said opening to close the same.

11. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, means on said gate member for guiding said paper across said adhesive applying opening to apply adhesive to the paper, whereby said gate member may be swung open for loading a roll of paper in said compartment and said guiding means being thereby swung away to permit free insertion of said paper between said adhesive applying opening and said guiding means, and members extending angularly inwardly of the adhesive applying opening at the opposite ends thereof for contacting said paper at the edges thereof to seal the opening but permitting flow of said fluid to the edges of the paper.

12. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate

member, said receptacle having an adhesive applying opening therein, means on said gate member for guiding said paper across said opening to apply adhesive to the paper, whereby said gate member may be swung open for loading a roll of paper in said compartment and said guiding means being thereby swung away to permit free insertion of said paper between said adhesive applying opening and said guiding means, and removable and replaceable members extending angularly inwardly of said adhesive applying opening at the opposite ends thereof for contacting said paper at the edges thereof to seal the opening but permitting flow of said fluid to the edges of the paper.

13. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, means on said gate member for guiding said paper across said adhesive applying opening to apply adhesive to the paper, whereby said gate member may be swung open for loading a roll of paper in said compartment and said guiding means being thereby swung away to permit free insertion of said paper between said adhesive applying opening and said guiding means, said guiding means including spaced yieldable elements on opposite sides of said adhesive applying opening for urging said paper against said opening to close the same, and means associated with said guiding means for adjusting the pressure of said paper against said adhesive applying opening.

14. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, means on said gate member for guiding said paper across said adhesive applying opening to apply adhesive to the paper, whereby said gate member may be swung open for loading a roll of paper in said compartment and said guiding means being thereby swung away to permit free insertion of said paper between said adhesive applying opening and said guiding means, said guiding means including spaced yieldable elements on opposite sides of said adhesive applying opening for urging said paper against said opening to close the same, and manually controlled means associated with said guiding means for adjusting the pressure of said paper against said adhesive applying opening.

15. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, means on said gate member for guiding said paper across said adhesive applying opening to apply adhesive to

the paper, whereby said gate member may be swung open for loading a roll of paper in said compartment and said guiding means being thereby swung away to permit free insertion of said paper between said adhesive applying opening and said guiding means, and means for flexing said paper over the lower edge of said opening to seal the same.

16. A paper hanging machine, comprising a casing, a receptacle in said casing for adhesive fluid, a compartment adapted to receive a roll of paper therein associated with said receptacle, a gate member swingably mounted on said casing to provide an opening into said compartment, means for releasably securing said gate member to said casing in the closed position of said gate member, said receptacle having an adhesive applying opening therein, means on said gate member for guiding said paper across said adhesive applying opening to apply adhesive to the paper, whereby said gate member may be swung open for loading a roll of paper in said compartment and said guiding means being thereby swung away to permit free insertion of said paper between said adhesive applying opening and said guiding means, means for flexing said paper over the lower edge of said adhesive applying opening to seal the same, and manually controlled means associated with said guiding means for adjusting the pressure of said paper against said adhesive applying opening.

17. A paper hanging machine, comprising a casing for containing adhesive fluid, means for supporting a roll of paper in association therewith, said casing having an adhesive applying opening therein, means for guiding said paper across said opening to apply adhesive to the paper, and a flexible element associated with said casing, said flexible element including two members adjustable angularly to each other whereby said element may be used for pressing said paper into corner surfaces as said paper is stripped from said machine.

18. A paper hanging machine comprising a casing, said casing having therein a receptacle for adhesive and also having therein a compartment for receiving a roll of paper, said receptacle having an adhesive dispensing opening therein, and said casing having a paper dispensing opening, means for guiding paper from said roll in association with said adhesive dispensing opening and out of said paper dispensing opening to be applied on a surface, and cutter means mounted on said casing for width-wise adjustment thereon and operable against paper issuing from said dispensing opening to cut the same to width.

19. A paper hanging machine comprising a casing, said casing having therein a receptacle for adhesive and also having therein a compartment for receiving a roll of paper, said receptacle having an adhesive dispensing opening therein, and said casing having a paper dispensing opening, and means for guiding paper from said roll in association with said adhesive dispensing opening and out of said paper dispensing opening to be applied on a surface, said guiding means including spaced rollers on opposite sides of said adhesive applying opening for urging said paper against said opening to close the same.

20. A paper hanging machine comprising a casing, said casing having therein a receptacle for adhesive and also having therein a compartment for receiving a roll of paper, said receptacle having an adhesive dispensing opening

therein, and said casing having a paper dispensing opening, means for guiding paper from said roll in association with said adhesive dispensing opening and out of said paper dispensing opening to be applied on a surface, and a brush mounted on the outside of the casing for applying paper issuing therefrom onto a surface, said brush having brush elements adjustable to different angles with each other for applying paper to corner surfaces.

21. A paper hanging machine comprising a casing, said casing having therein a receptacle for adhesive and also having therein a compart-

ment for receiving a roll of paper, said receptacle having an adhesive dispensing opening therein, and said casing having a paper dispensing opening, means for guiding paper from said roll in association with said adhesive dispensing opening and out of said paper dispensing opening to be applied on a surface, said casing having a slot across the same over which said paper passes after it issues from said dispensing opening, and cutter means retained inside of said casing and 10 operable in said slot for cutting to length paper withdrawn from said casing.

WALLACE H. JOHNSON.
